UNITED STATES PATENT OFFICE.

HENRY M. WITTER, OF WORCESTER, MASSACHUSETTS, ASSIGNOR TO GEORGE CROMPTON, OF SAME PLACE.

IMPROVEMENT IN LOOMS FOR WEAVING WEBBING.

Specification forming part of Letters Patent No. 170,458, dated November 30, 1875; application filed October 6, 1875.

To all whom it may concern:

Be it known that I, HENRY M. WITTER, of Worcester, in the county of Worcester and State of Massachusetts, have invented an Improved Loom for Weaving Webbing, of which the following is a specification:

This invention relates to a loom for weaving fabrics partly tubular and partly solid, the fabric being applicable for webbing for sash-cinges, and for other purposes.

The invention is shown as applied to an ordinary Crompton loom, having vertical side levers with notched jacks pivoted thereto, and put in position for the action of the elevator or depressor by the action of fingers moved by pins on a pattern-cylinder; but the invention may be applied to any other well-known class of fancy looms.

The invention consists in a harness-lever, a connected jack, a lever, and a pattern mechanism for controlling the jack, in combination with a second lever or finger, and pins or protuberances on a pattern-cylinder, to give additional movements to the jack-operating lever, as and for the purpose hereinafter set forth. Also, in a pattern mechanism, a jack and two levers or fingers, for moving it, each lever or finger being operated by independent pins or projections, in combination with a pattern-cam for controlling the fulcrum of one or both levers, and in other features of invention, as will be hereinafter described.

Figure 1 is a side view of sufficient of a loom to illustrate one application of my invention, and Figs. 2 and 3 are details.

In the drawing, I show five levers, adapted to be connected by cords with harness-frames, and to be operated to form sheds, as described in United States Patent No. 51,928, and the reissues thereof. Four of these upright levers with their hooked or notched jacks, and fingers or jack-operating levers and their lines of pattern-surfaces, operate to lift their connected harness-frames, so as to weave a tubular fabric, and the fifth harness has its jack controlled by two fingers and two rows of pattern-projections, so as to place the

warps carried by it either entirely in one side or part of the tubular fabric, so as not to interrupt the tube, or into first one part for one pick, and then into the other side or part for another pick, thereby uniting both sides or parts by stitching warps and forming a solid fabric.

In the drawing, *a* are the long upright harness-levers, notched for the attachment of cords and harness-frames, and each lever has pivoted to it a jack, *b*, connected with a finger or lever, *c*, having its fulcrum on a rod, *d*, and resting on a pattern-surface or mechanism, *e*, of any well-known construction. These jacks are engaged by lifters and depressors *f*, *g*, and the parts so far described are all as usual.

Of five harness-levers, *a*, employed in this embodiment of my invention, (but one lever, however, being seen, the others being behind it in Fig. 1,) four of their connected harness-frames carry warps for weaving a tubular fabric, the pins in the pattern lifting them in the order necessary to weave a tube, which is well understood, and the draft of the mounting need not be shown.

The fifth harness-lever, the one shown in Fig. 1, is adapted to be connected with a harness-frame provided with a greater or less number of warps, called "binding-warps," and in addition to its usual jack, finger, and pins or protuberances for moving the finger *c*, I employ a second lever or finger, *h*, having its fulcrum at *d*, and provided at its forward end with a pin or projection, *i*, to engage and lift its adjacent finger, *c*, this additional finger being controlled by a separate and distinct row of pattern-pins or projections, either on the main pattern-surface or by the side of it, as shown, or on an independent pattern-surface, which might be brought into place intermittently, to lift the finger *h* at the desired times, or as the exigencies of the pattern being woven demand. The lever or finger *h*, at one end, is provided with an enlarged or elongated slot, *j*, to fit over its fulcrum, *d*, and it has also an ear or pin, *k*, to project within the path of, and be acted on

by, a finger-controlling pattern or cam, *l*, carried on shaft *d*, and actuated through a ratchet, *m*, and pawl *n*, the carrying-arm *o* of which is moved by a pin or cam, on, as shown in this instance, the pattern-shaft. The finger-controlling pattern *l* has a depressed or removed part, *p*.

When the ear *k* rests on the periphery of the pattern *l*, the lever *h*, when acted on by the pins or projections of the pattern-surface *e*, will be raised at its outer end, its pin *i* lifting the finger or lever *c*; but when the ear comes opposite the depressed portion *p*, then a pin acting on *h* will raise the slotted end of *h*, and will not raise its other end and the finger *c*.

The pins or projections on the pattern for operating these two adjacent fingers or levers *h c*, controlling the movement of the jack connected with the harness-frame carrying the binding-warps, operate as follows, viz: During the time the tube is being woven, the ear *k* of lever *h* rests in the open part *p* of pattern *l*, so that, if moved by a pin on the pattern-cylinder *e*, it will not lift finger or lever *c*, and the pins under or in connection with finger *c* so control the movement of the finger *c*, hooked jack *b*, and binding-warp-harness-frame, that the binding-warps are retained altogether on one side of the tube, being woven by the harness-frames connected with the other jacks, and the tube is not interrupted; but when a tubular fabric of sufficient length has been woven, the length of the tube being controlled by the space *p* in the pattern *l*, then the ear *k* meets the periphery of the pattern *l*, and secures the end of lever *h* on its fulcrum *d*, so that lever *h*, when lifted by a pin or projection on the pattern-surface *e*, will lift the finger *c*, and at such times as to cause the binding-warps to be placed for one pick into position with the warps for one part of the tube, and then for another pick into the warps forming the other side of the tube, and the binding-warps so introduced into each side will tie together the tube-portions, making a solid fabric for a length controlled by the periphery of the pattern *l*.

When weaving solid, the finger or lever *c* derives its motion from finger or lever *h*; but it is evident that in some patterns it will at times happen that the finger *c* will have a pin under it, to raise it at the proper time to place the binding-warps in the then proper shed to tie the two webs of the tube together, and then it would be unnecessary for that pick to lift the finger *c* through the finger *h* and its pin.

In some looms for complicated patterns, I propose to combine with each lever *c* a lever, *h*, and a pattern for the pivoted end of the lever, and pins for each lever, as set forth. Instead of having the pins or protuberances for moving the levers *h* on the same cylinder

or surface as are the pins for moving fingers *c*, I may employ a separate cylinder or chain, and throw it into action as desired, in connection with levers *h*.

When using the patterns *l* side by side, I prefer to make them, so that where one has a space the other will have a projection, and where one has an acting face the other will have a space, the alternate patterns being conversely arranged as to actuating surfaces and spaces.

The spaces and operating parts of patterns *l* will be determined by the length of the tubular and connected spaces desired in the web.

This invention may be used for weaving bags, pouches, pockets, and other similar articles.

Other forms of notched jacks than those described, and substantially such as shown in the well-known Crompton looms, may be lifted by two levers and two sets of pins, one set for each lever, as and for the purpose described.

I may employ two levers for the binding-warp harness-frame, substantially like *h* and *c*, each lever having pattern-surface to move it, and one being provided with a lever-controlling cam, *l*, as described; but this arrangement I do not consider as good as the one shown in the drawings.

Instead of pin *i* projecting from *h*, I might use a pin projecting from *c*, and resting in a slot in *h*.

In operation, the warps forming one side of the tubular portion, or the faces which would form a tube if not tied together by independent binding-warps, always remain on the same side of the fabric, whether weaving tube or solid, and in changing from tube to solid the tube-forming harness do not change their weave.

I claim—

1. A harness-lever adapted to be connected with a harness-frame, a connected jack, a lever to move the jack, and a pattern-surface to move the lever, in combination with a second lever and its actuating pattern-surface to move the lever, connected with and moving the jack, substantially as described.

2. A harness-lever, adapted to be connected with a harness-frame, a connected jack, two jack-operating levers, and two rows of pattern-surfaces for actuating the jack-levers, in combination with a lever-controlling pattern, *l*, substantially as described.

3. A lever and pins or protuberances on a pattern-surface, for actuating it, in combination with a second lever, provided with a slotted end, and adapted to raise the former lever, and with pins or protuberances for raising, and a pattern-surface for controlling, the slotted end of the latter lever, substantially as described.

4. The combination of harness-operating mechanism controlled by pattern-surfaces

adapted to form sheds in warps to weave a tubular fabric, with harness-operating devices adapted to move a harness-frame provided with binding-warp, and with mechanism to move the lever controlling such binding-warp harness-frame, whereby a binding-warp may be introduced into one or both sides of the tubular part, to permit the fabric to remain as a tube, or to connect the regularly-woven

sides to form a solid fabric, substantially as described.

In testimony whereof I have signed my name to this specification in the presence of two subscribing witnesses.

HENRY M. WITTER.
